[57] CLAIM

The ornamental design for a plectrum, as shown and described.

DESCRIPTION

FIG. 1 is a top plan view of a plectrum showing my new design, the undisclosed bottom plan view being a mirror image thereof;

FIG. 2 is a side elevational view of both sides of the plectrum shown in FIG. 1;

FIG. 3 is an end view of the plectrum shown in FIGS. 1; and,

FIG. 4 is a top plan view of a second embodiment of the plectrum, the undisclosed bottom plan view being a mirror image thereof.
